DOLL

Thomas Dam Poulsen, Gjoel Pr. Aabybro, Denmark

Filed Oct. 6, 1960, Ser. No. 62,391

Term of patent 14 years

(Cl. D34—4)

Fig. 1.

Fig. 2.

Fig. 3.

FIG. 1 is a front elevational view of the doll;
FIG. 2 is a side perspective view thereof;
FIG. 3 is an elevational view from another side.
The view from the other side of the doll is identical with that shown in FIG. 2 with the exception of the pocket on the dress.

I claim:

The ornamental design for a doll, as shown and described.
